UNITED STATES PATENT OFFICE.

OLUF OPSJÖN, OF SALTESE, MONTANA.

EGG-CARTON.

1,125,872.

Specification of Letters Patent.

Patented Jan. 19, 1915.

Application filed November 3, 1913. Serial No. 799,026.

To all whom it may concern:

Be it known that I, OLUF OPSJÖN, citizen of the United States, residing at Saltese, in the county of Missoula and State of Montana, have invented certain new and useful Improvements in Egg-Cartons, of which the following is a specification.

The subject-matter of the present invention is directed to new and useful improvements in cartons or holders for eggs, and as its principal object aims to provide a device of this character which is peculiarly adapted for receiving eggs and protecting them against breakage during transit.

15 A further object of this invention aims to provide an egg carton which is in its preferred embodiment formed in the nature of a pasteboard mailing tube which is divided into a number of individual egg receiving 20 compartments, so that each egg may be incased in a pasteboard housing, thus guarding it against contact with the other eggs in the carton and with foreign objects.

25 A still further object is to form the carton or tube from a rectangular blank of pasteboard, so that the tubes may be shipped in large quantities, occupying a minimum space and being adapted to be molded into assembled form at the time they are put into 30 use.

The above and additional objects are accomplished by such means as are illustrated in the accompanying drawings, described in the following specification and then more 35 particularly pointed out in the claims which are appended hereto and form a part of this application.

With reference to the drawings, wherein there has been illustrated the preferred embodiment of this invention as it is reduced to practice, and throughout the several views of which similar reference numerals designate corresponding parts, Figure 1 is a plan view of the blank from which the preferred 45 form of tubular carton is formed; Fig. 2 is a perspective view illustrating the carton and the closure in assembled relation; Fig. 3 is a detail perspective view of the filler strip in which the eggs or other articles are

wrapped before being placed in the several compartments of the carton; Fig. 4 is a section on the line 4—4 of Fig. 2; Fig. 5 is a perspective view of the tubular body member with the cover removed, portions of the wall of the tube being broken away to more 50 clearly illustrate the interior arrangement of the partition walls and filler strips; and Fig. 6 is a perspective view of the channel-shaped closure member employed in sealing the openings through which the eggs are 55 inserted when being placed within the compartments of the carton.

The preferred embodiment of this invention, as illustrated in Fig. 5 particularly, includes two main elements, a body tube 10 60 and a closure 11.

The body tube 10, which is best illustrated in Fig. 1, wherein is shown a plan view of the blank from which it is manufactured, is preferably formed from a rectangular sheet of pasteboard. The material from which the body tube of the carton is formed is, as stated, preferably pasteboard of medium thickness, but it is, of course, apparent that if so desired the tube may be 70 fashioned of any suitable composition which may be found advantageous without departing in any way from the spirit of this invention.

In the preferred form, the rectangular 80 sheet of pasteboard 12, referred to above, is in length slightly greater than the combined lengths of six eggs, although the tube may be made to accommodate a greater or less number of eggs as circumstances may 85 require. This member 12, which as indicated forms the tube member of the device, is formed with a longitudinally extending series of spaced tongues 13 which are circular in shape and are formed by subscribing 90 six circles in the line of the longitudinal center of the member 12. It will be noted upon reference to Fig. 1 that the centers of these circles are equidistantly spaced longitudinally on the member 12, and that the 95 tongues are produced by slitting the pasteboard around the line of the circles all the way except a slight distance on each side

of the longitudinal center line of the member. It will be noted upon reference to Fig. 1 that by leaving the portions of the pasteboard uncut on each side of the center as at 15, a connecting portion is formed between each tongue 13 and the body blank 12. The purpose of thus attaching the tongues to the body of the tube blank is to permit the tongues to be bent at right angles to the member 12, so that they will remain attached thereto. This construction is necessary in order that the member 12 may be longitudinally rolled to produce a tube which incases the tongues 13 as in Fig. 4. It will be noted upon reference to this figure that when the tongues are bent at right angles and the blank has been rolled to assume the form of a cylindrical tube, the tongues 13 divide the tube thus produced into a number of individual compartments which in the preferred embodiment will be six. It may be desirable to mention in this connection that the diameter of the tongues 13 is slightly greater than the cross sectional diameter of an ordinary egg, being thus formed so that the filler strips, to be hereinafter described, may be wrapped around each egg and placed in the egg receiving compartments. It is to be further noted that the width of the blank 12 is approximately equal to $2\pi R$ R in this equation being the radius of the circle from which the tongues 13 are described.

In inserting the eggs into the individual compartments which are provided in the tube 10 in the manner above described, each egg is first wrapped in one of the filler strips illustrated in detail in Fig. 3, and designated by the numeral 16. Each of these filler strips is preferably rectangular in shape and of such dimensions as may be accommodated in the egg receiving chambers. In the preferred embodiment, the filler strips are formed of corrugated pasteboard, but cotton batting, a fabric, or any other element of a similar nature may be employed, it being, of course, obvious in this connection that the selection of the material from which the filler strips are formed is purely an arbitrary matter, and one to be governed solely by the circumstances and conditions. The only requisite of the filler strips is that they be of such nature that they will effectually guard the eggs against shocks and jars.

After the eggs have been placed within the receiving compartments of the tube 10, the closure member 11 is applied to it. This closure member 11 consists in the preferred embodiment of a channel shaped sheet of pasteboard, as will be noted upon particular reference to Fig. 4, in which this feature of the invention is best illustrated. This closure is, of course, placed longitudinally on the tube 10, and is arranged to

cover the openings which are produced by bending the members 13 as above set forth.

A number of gummed ribbons 17, which may be of manila paper or some suitable fabric, such as cheese-cloth and the like, are carried by the closure 11, and are designed to be wound around and applied to the tube 10 in the well known manner, as shown in Fig. 2.

When the blank 12 of the tube has been bent into tubular form, a piece of cheese-cloth or linen is applied by gluing to the free edges of the blank so that they will be held in the desired relation to one another. Referring again to Fig. 1, it will be noted that a terminal tongue is formed on one end of the member 12, and that this tongue extends beyond the edge thereof. It will be obvious that this tongue is employed as a closure for the end of the tube.

While the preferred embodiment of this invention employs as a means for holding the closure on the tube 10, a number of gummed paper or fabric ribbons, these elements may, of course, be replaced by metallic clamping rings of the well known type.

In reduction to practice, I have found that the form of my invention illustrated in the drawings, and referred to in the above description as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. As an article of manufacture, a container of the class described including a tubular body member formed from a single blank of material having a plurality of substantially circular clefts cut in spaced relation to each other along a longitudinal median line, the material freed by the clefts being adapted to be bent inwardly, after the blank is rolled, forming partition walls which divide the body member into a plurality of individual compartments, a channel-shaped closure adapted to be fitted over the openings which are formed by bending the partition walls inwardly, flexible means for holding the free edges of the blank in closed relation, and flexible means for holding the closure in position on the body member.

2. As an article of manufacture, a blank for forming cylindrical containers, said blank being substantially rectangular and being provided with a longitudinally extending, medially disposed series of spaced clefts, each of which frees a substantially cylindrical portion adapted to be bent in-

wardly forming a partition wall when the blank is rolled into cylindrical form, and a substantially circular tab formed on one terminal of the blank and extending beyond the edge thereof, said tab being adapted to constitute a terminal closure for one end compartment when the blank is rolled into cylindrical form.

In testimony whereof I affix my signature in presence of witnesses.

OLUF OPSJÖN. [L. S.]
